UNITED STATES PATENT OFFICE

GEORGE HENRY COLLINS, OF BRENTFORD, ENGLAND

FIRE BAR

Application filed April 4, 1927, Serial No. 180,843, and in Great Britain April 16, 1926.

This invention relates to fire bars for furnaces, such for example as boiler furnaces, and it has for its object improvements by which certain advantages shall be obtained.

5 More particularly, the invention relates to a fire bar of the kind having a central body part or bar proper with vertical ribs on each side.

According to the present invention, the vertical ribs are tapered from back to front and extend for a portion or the whole depth of the bar, the tapering commencing at a point below the upper surface of the bar and extending to the lower ends of the ribs.

15 One form of fire bar in accordance with the invention will now be described with reference to the accompanying drawings in which:—

Fig. 1 is a side elevation;

20 Fig. 2 is a plan;

Fig. 3 is a side elevation of a portion of a bar to an enlarged scale; and

Fig. 4 is a section on the line A—B of Fig. 3.

25 The centre body part 1 has a plurality of vertical evenly spaced ribs 2 on each side extending outwardly therefrom and from the top to the bottom of the bar, those on one side being staggered in relation to those on the other side. The sides 3 of the ribs are inclined so that the spaces 4 between adjacent ribs are of gradually increasing cross sectional area from the top to the bottom. The slots 4 at the top face of the bar are 35 narrower than the ribs 2 so that each slot is sealed and isolated from the other slots by a rib on an adjacent bar. Each of the ribs 2 is tapered from the top towards the bottom, as shown at 5, the tapering commencing a short distance below the top face as shown so that short vertical sides 6 are provided. From a point below the top face of the bar the ribs are further tapered from the back adjacent the central body part 1 to

40 the front as shown at 7, 7, the tapering extending to the lower ends of the ribs. At each end the bar is provided with shoulders 8 and it is of exactly the same shape at each end so that it may be reversed in the furnace if required. The bottom edge 9 of the

bar is of usual form, namely, curved so that it has a greater depth in the middle than at the ends.

The top face 10 of the bar may be flat, convex or concave.

Though the bar shown in the drawings is of the same shape at each end it will be understood that the ends may be of any shape required in any particular furnace.

What I claim is:—

1. A fire bar having a central body part, shoulder portions of similar shape in plan at the ends thereof wider than said body part and a like number of vertical integral ribs with parallel sides at the surface extending outwardly from said body part on each side all to the same distance as the shoulder portions, said ribs being tapered from back to front the tapering commencing at a point below the upper surface of the bar and extending to the lower ends of the ribs and the spaces between the ribs at the surface of the bar being narrower than the width of the ribs.

2. A fire bar having a central body part, shoulder portions of similar shape in plan at the ends thereof wider than said body part and a like number of vertical integral ribs with parallel sides at the surface extending outwardly from said body part on each side all to the same distance as the shoulder portions, said ribs being tapered from back to front the tapering commencing at a point below the upper surface of the bar and extending to the lower ends of the ribs, the ribs being also tapered from the top towards the bottom and the spaces between the ribs at the surface of the bar being narrower than the widths of the ribs.

3. A fire bar having a central body part, shoulder portions of similar shape in plan at the ends thereof wider than said body part and a like number of vertical integral ribs with parallel sides at the surface extending outwardly from said body part on each side all to the same distance as the shoulder portions, said ribs being tapered from back to front, the tapering commencing at a point below the upper surface of the bar and extending to the lower ends of the ribs, the

ribs being also tapered from the top towards the bottom with the tapering commencing a short distance below the top surface of the bar and the spaces between the ribs at the 5 surface of the bar being narrower than the width of the ribs.

Dated this 24th day of March, 1927.

GEORGE HENRY COLLINS.
